COMBINED CLOSURE AND FLASK OR SIMILAR ARTICLE

William J. Hannon, Jr., Dorchester, Mass., assignor to The Macbick Company, Cambridge, Mass., a corporation of Massachusetts

Original design application Feb. 4, 1963, Ser. No. 73,427.
Divided and this application Jan. 10, 1964, Ser. No.
78,552.

Term of patent 14 years

(Cl. D58—8)

FIG. 1

FIG. 3

FIG. 1 is a perspective view of a combined closure and flask or similar article embodying my new design;

FIG. 2 is a fragmentary side elevational view thereof,
and

FIG. 3 is a top plan view thereof.

This application is a division of my earlier filed application Serial Number D. 73,427, filed February 4, 1963.

I claim:

The ornamental design for a combined closure and flask or similar article, substantially as shown and described.
